Patented Aug. 19, 1913.

UNITED STATES PATENT OFFICE.

ALLEN D. CARDWELL, OF NEW YORK, N. Y.

CONTROLLING SYSTEM FOR RECEIVING APPARATUS.

1,070,945.

Specification of Letters Patent. Patented Aug. 19, 1913.

Application filed November 14, 1911. Serial No. 660,205. Renewed December 5, 1912. Serial No. 735,175.

To all whom it may concern:

Be it known that I, ALLEN D. CARDWELL, a citizen of the United States, and resident of New York city, borough of Brooklyn, in the county of Kings and State of New York, have invented certain new and useful Improvements in Controlling Systems for Receiving Apparatus, of which the following is a specification.

10 My invention relates to improvements in controlling systems for receiving apparatus for signaling systems, and more particularly to systems in which characteristic kinds of impulses are sent over a main line from a 15 central or transmitting station by selective apparatus. The invention is intended by me for use more particularly in connection with recording apparatus, such as described in my application for telegraph-typewriter, 20 Serial No. 598,755, filed December 22, 1910.

The invention comprises a line relay and contacts therefor and a plurality of groups of working magnets, one or more magnets being selectively energized on the coming in 25 of an impulse. These magnets are included in circuits which are completely closed through a line relay contact, so that an energized magnet will perform the work required of it immediately upon the coming in 30 of the impulse. For the purpose of holding the selected working magnet energized until the coming in of all of the impulses, I provide relays divided into groups similar to the divisions of the working magnets, which 35 relays, on the coming in of an impulse, will close a contact in a holding circuit, which holding circuit remains energized upon the breaking of the impulse. Furthermore, I provide switching relays to shift the circuits 40 of the line relay contacts to the groups of magnets successively.

The invention will be understood from the following description taken in connection with the accompanying diagrammatic view 45 in which the reference letters A, B and C designate a group of working magnets; D, E and F, a second group of working magnets; and G, H and I a third group of working magnets. These magnets are included in circuits which also include line relay contacts 1 and 2, the tongue 3 of the main line relay L being normally held in a central position relative to said contacts and

connected to one pole of a local battery 4, at point 4^a, the other pole of said battery being grounded. As the impulses come in over line *a* either the contact 1 or the contact 2 will be closed, and in so doing one or more magnets of each group will be successively energized, that is in the first group either 55 the magnet A alone, or B alone, or A and C or B and C; in the second group either D alone, or E alone, or D and F or E and F; in the third group either magnet G alone, or H alone, or G and I or H and I. According to the system adopted by me the magnets A, D and G will be energized on the coming in of a positive impulse irrespective of duration, through line relay L closing contact 1. The magnets B, E and H will be 65 energized upon the coming in of a negative impulse, irrespective of duration, through line relay L closing contact 2; the magnets C, F and I will be energized upon the coming in of a prolonged impulse irrespective 70 of polarity.

In addition to the working circuits for the magnets of each group I provide holding circuits which include in the first group relays A', B', C'; in the second group relays 75 D', E', F'; in the third group relays G', H', I'. The function of these relays is to close a contact in the corresponding holding circuit to maintain energized the selected working magnet until the breaking of the 80 final impulse.

To switch or shift the circuits of the line relay contacts, I provide relays R and S, the former for switching the circuits of the line relay contacts from the first to the second group of magnets upon the breaking of the first impulse, and the latter for shifting the circuits of the line relay contacts from the second to the third group of magnets upon 90 the breaking of the second impulse. For the purpose of illustration, I have shown but three groups of working magnets, but if more are employed there will be a shifting magnet for each additional relay. The relay T shown in the third group of magnets is for the purpose, among other things, of closing the circuit of a magnet J, as will be more fully explained hereafter. Relays A', B', D', E', G' and H', and the shifting relays R and S are single wound. The relays C', F' and I' 95 are double wound.

Any suitable arrangement or sequence of impulses may be adopted and the apparatus and its method of operation will be readily understood by assuming that the working magnets A, E and F, G are to be energized, requiring, according to the system adopted, a short positive, a long negative, and a short positive impulse to energize said magnets in the sequence given. The first or short positive impulse on the main line a will close contact 1, thus completely closing and energizing a working circuit from local battery to point 4^a, tongue 3 of main line relay L, contact 1, normally closed contact 5, normally closed contact 6, point 7, through working magnet A, point 8, point 9; also from point 7 through relay A' in multiple with the working magnet A to point 9, to point 10, through left hand winding of relay C' to ground x . When magnet A is thus energized, it performs the work required of it which, in the particular instance described in my previous application, is to advance a type wheel the first step toward printing position. Relay C', responding only to a long impulse, will not be sufficiently energized to attract its armature.

When relay A' is energized, it closes a contact 11 in a second or holding circuit, but said circuit will not be energized as long as the line relay contact 1 remains closed, principally because of the resistance of the switching relay R which is included in the holding circuit. The holding circuit, however, will be energized upon the breaking of the first impulse, and may be traced as follows: from point 4^a through normally closed contact 12, point 13, point 14, through shifting relay R to contact 11, closed when relay A' is energized on the closing of contact 1, armature of relay A', through relay A', and working magnet A in multiple therewith, to point 9, to point 10, left-hand winding of relay C', to ground x . This circuit through the switching relay R will maintain said relay and the working magnet A and relay A' energized until the breaking of the final impulse. When shifting relay R is thus energized, contact 15 will be closed so that current will flow from point 10 directly to ground x' , short-circuiting the left-hand winding of relay C' so that it will not be operated by the holding circuit. The movement of the armature of relay R which closes contact 15 will open the normally closed contacts 6 and 16 and close the normally open contacts 17 and 18, thus shifting the circuits of the line relay contacts 1 and 2 to the second group of magnets and their corresponding relays.

The second impulse will energize the magnets E and F and, under the assumption stated, being a long negative, line relay contact 2 will be closed, thus closing an operating circuit and a holding circuit for

the magnet or magnets of the second group which are to be energized, although, similarly to the holding circuit before described in connection with the first group of magnets, current will not operate relay S in the second holding circuit until contact 2 is opened. The operating circuit is as follows: point 4^a to contact 2, to normally closed contact 19; to previously closed contact 18, to point 20, through working magnet E and relay E' in multiple therewith, to point 21, closing contact 22, to point 23, left-hand winding of relay F', to ground x^2 . Since this is a long impulse, relay F' will be operated, closing contact 24 and permitting thereby current to flow from point 4^a through normally closed contact 12, to point 13, to point 25, through working magnet F to contact 24, armature of relay F', through right-hand winding of relay F', thus holding its armature attracted, to ground x^2 . When the magnets E and F are thus energized, they in turn will perform the particular work required of them, which, if in a telegraph typewriter of the character described in my said previous application, will advance the type wheel its second step toward printing position.

The holding circuit through switching relay S, which will be closed on the closing of contact 22, but through which current will not flow until the second impulse is broken, may be traced as follows: from point 4^a through normally closed contacts 12, point 13, point 25, through relay S to contact 22 of relay E', which was closed on the coming in of the second impulse, through relay E' and working magnet E in multiple therewith, to point 21, to point 23, through left-hand winding of relay F' to ground x^2 , thereby operating switching relay S to close the normally open contact 26 and to open the normally closed contacts 5 and 19, and to close the normally open contacts 27 and 28, thereby switching the line relay contacts 1 and 2 to the third group of working magnets and their relays. At the same time the left-hand winding of relay F' is short-circuited and the current flows from point 23 through contact 26 to ground x^2 .

The third and final impulse, under the conditions stated, being a short positive, an operating circuit will be closed through which current will flow as follows: from point 4^a contact 1, contact 27, which as stated, was closed on the breaking of the second impulse, point 29, working magnet G and relay G' in multiple therewith, point 30, point 31, left-hand winding of relay I' to ground x^4 . This being a short impulse, relay I will not be sufficiently energized to attract its armature. When magnet G is thus energized, it performs the work required of it, which, in the assumed use, will be the movement of the type wheel to its

ultimate printing position. This being the final impulse preparatory to the accomplishment of the result desired, which result is attained on the breaking of the final impulse, a circuit is established through a relay T, when contact 33 is closed but through which current does not flow until third impulse is broken, owing principally to the resistance of relay T, as follows: 5 point 4*, closed contacts 12, point 13; point 32, relay T, contact 33, armature of relay G', through relay G' and magnet G to point 30, point 31, through left hand winding of relay I' to ground. x*.

10 For the purpose of illustration, I have shown a magnet J carrying on its armature K a hammer U, said armature being attracted when magnet J is energized on the breaking of the final impulse to effect the 15 printing of the selected character. On the breaking of the final impulse, relay T will be operated to close contacts 34 and 35, the former short circuiting the left hand winding of relay I' and the latter closing the 20 circuit of printing magnet J. The instant hammer U delivers its blow, the free end of armature K will separate contacts 12, thus opening all of the holding circuits and restoring the mechanism to normal condition. 25

25 When relay T is deenergized, contacts 35 will be separated, thus deenergizing magnet J. Armature K will then be retracted by its spring and contacts 12 permitted to close.

Although I have described as a particular 30 use of the present invention the recording of a character or signal set up at the transmitting station, it is obvious that the magnet J instead of operating a hammer of a typewriter apparatus may be connected to 35 mechanism which will set a visual signal, or will set in operation an audible signal.

Any suitable sequence of impulses may be adopted for the purpose of closing the circuits of the working magnets selected. For 40 instance, there may be adopted for transmission over the main line a, positive and negative impulses for short or long duration, either or each of which may be combined in any desired manner for each character transmitted or each function performed, viz: three impulses of similar duration and of similar polarity following each other, to cause one operation of the system; three impulses, two of similar polarity and duration and one of a different polarity or duration, and so on, for effecting operation of the 45 system. In the example illustrated having three sets of relays controlled by any desired group of three line impulses, sixty-four combinations of impulses may be carried out, and if more sets of relays are installed in the system, the number of combinations of impulses will be increased in proportion.

50 From the foregoing description, the cir-

cuits for any particular set of working magnets may be readily traced, it being understood that on the closing of a line relay contact two circuits will be established; first, an operating circuit through which current will immediately flow to energize the selected working magnet and to cause it to perform the work required of it, and also to energize the corresponding relay to close a contact in a holding circuit through which holding circuit current will flow on the opening of the line relay contact; and second, that when current flows through the holding circuit, the switching relay will be energized to shift the circuits of the line 70 relay contacts to the next succeeding group of working magnets and their relays. The system thus differs from that of my said former application in that in said former application the closing of line relay contact 75 does not directly close a circuit through the selected working magnet, but through the corresponding relay which closes the circuit of the magnet.

Having now described my invention what I claim is:-

1. A controlling system of the character described comprising a plurality of groups of working magnets, an operating circuit and a holding circuit for each group of magnets, means for energizing the operating circuit and for limiting the flow of current through the holding circuit until the operating circuit is opened.

2. A controlling system of the character described comprising a plurality of groups of working magnets, an operating circuit and a holding circuit for each group, means for energizing the operating circuit, and a resistance in the holding circuit to limit the flow of current therethrough until the operating circuit is opened.

3. A controlling system of the character described comprising a plurality of groups of working magnets, an operating circuit and a holding circuit including said magnets, a line relay and contacts therefor, means whereby when a line relay contact is closed an operating circuit and a holding circuit will be closed through a selected magnet and its relay, and means to limit the flow of current through the holding circuit until the line contact is opened.

4. A controlling system of the character described, comprising a plurality of groups of working magnets, means for selectively energizing a magnet or magnets of each group and at the same time closing a holding circuit through said magnet or magnets, and means to permit operation of the holding circuit when the energizing circuit is open.

5. A controlling system of the character described comprising a plurality of groups of working magnets, an operating circuit

and a holding circuit for each group of magnets, means for simultaneously closing the operating circuit and the holding circuit through a magnet or magnets of a group, and means to permit operation of the holding circuit when the operating circuit is open.

6. A controlling system of the character described comprising a plurality of groups of working magnets, groups of relays corresponding to said magnets, an operating circuit and a holding circuit for each group of magnets and their corresponding relays, means for closing the operating circuit of a magnet or magnets of a group and energizing the corresponding relay to close a contact in its holding circuit, a relay in said holding circuit, and means to permit operation of said relay when the operating circuit has been opened.

7. A controlling system of the character described comprising a plurality of groups of working magnets, an operating circuit and a holding circuit for each group of magnets, a line relay and contacts therefor, switching relays in said holding circuits, and means for closing a contact in a holding circuit when the operating circuit is energized upon the closing of a line relay contact, thereby short circuiting the corresponding switching relay while the line relay contact is closed.

8. A controlling system of the character described comprising a plurality of groups of working magnets, an operating circuit and a holding circuit for each group of magnets, a line relay and contacts therefor, switching relays in said holding circuits, means for closing a contact in a holding circuit when the operating circuit is energized upon the closing of a line relay contact, thereby short circuiting the corresponding switching relay while the line relay contact is closed, and means for maintaining the holding circuits closed until all of the operating circuits have been energized.

9. A controlling system of the character described comprising a plurality of groups of working magnets, groups of relays corresponding to said magnets, an operating circuit and a holding circuit for each group of said magnets and relays, the corresponding working magnets and relays being subject to the same impulse, a line relay and contacts therefor, a switching relay in the holding circuit, and a normally open contact in said holding circuit adapted to be closed when a selected working magnet relay is energized.

10. An electric circuit controlling system comprising a working magnet, a relay corresponding to said magnet, an operating circuit for the magnet and for the relay, a holding circuit for the magnet and for the

relay, means for closing the operating circuit of said magnet and energizing said relay to close a contact in their holding circuits simultaneously, a relay in said holding circuit, means to prevent operation of said relay when the operating circuit is closed, and a circuit controlled by the last named relay.

11. A controlling system of the character described comprising a plurality of groups of working magnets, an operating circuit and a holding circuit for each group of magnets utilizing the same winding of each magnet, means for energizing the operating circuit and for limiting the flow of current through the holding circuit until the operating circuit is opened.

12. A controlling system of the character described comprising a plurality of groups of working magnets, an operating circuit and a holding circuit including said magnets utilizing the same winding of each magnet, a line relay and contacts therefor, means whereby when a line relay contact is closed an operating circuit and a holding circuit will be closed through a selected magnet and its relay, and means to limit the flow of current through the holding circuit until the line contact is open.

13. A controlling system of the character described comprising a plurality of groups of working magnets, an operating circuit and a holding circuit including said magnets, a line relay and contact therefor, said circuits utilizing the same windings in said magnets and relays respectively, means whereby when a line relay contact is closed an operating circuit and a holding circuit will be closed through a selected magnet and its relay, and means to limit the flow of current through the holding circuit until the line contact is open.

14. A controlling system of the character described, comprising a plurality of groups of working magnets, groups of relays corresponding to said magnets, an operating circuit and a holding circuit of each group of magnets and their corresponding relays utilizing the same windings of the magnets and relays respectively, means for closing the operating circuit of a magnet or magnets of a group and energizing the corresponding relay to close a contact through its holding circuit, a relay in said holding circuit, and means to permit operation of said relay when the operating circuit has been opened.

15. An electric circuit controlling system comprising a working magnet, a relay corresponding to said magnet, an operating circuit for the magnet and for the relay, a holding circuit for the magnet and for the relay, means for closing the operating circuit of said magnet and energizing said relay to close a contact in their holding cir-

cuits simultaneously, a relay in said holding circuit, means to prevent operation of said relay when the operating circuit is closed, means to maintain closed the circuit of said relay when the operating circuit of said first named relay is broken, and a circuit controlled by the second named relay.

Signed at New York city, in the county of New York, and State of New York, this 13th day of November, A. D. 1911.
